CLAIM

The ornamental design of a telephone, as shown and described.

DESCRIPTION

FIG. 1 is a top plan view thereof of a telephone showing my new design;

FIG. 2 is a front elevational view thereof;

FIG. 3 is a side elevational view thereof;

FIG. 4 is a bottom plan view thereof;

FIG. 5 is an isometric view thereof;
The broken line in all figures of portions of the electric cord are used to indicate continuity of cord between full line representation of the cord in these figures, and for convenience of drawing effort.

FIG. 1

FIG. 2

FIG. 3

FIG. 4

FIG. 5
